UNITED STATES PATENT OFFICE.

HUGH C. BOYLE AND JOHN MAUM, OF ELIZABETH, NEW JERSEY.

ENVELOP FOR WIRE COILS.

SPECIFICATION forming part of Letters Patent No. 777,395, dated December 13, 1904.

Application filed May 24, 1904. Serial No. 209,521. (No model.)

To all whom it may concern:

Be it known that we, HUGH C. BOYLE and JOHN MAUM, citizens of the United States, residing at Elizabeth, in the county of Union 5 and State of New Jersey, have invented new and useful Improvements in Envelops for Wire Coils, of which the following is a specification.

Our invention relates to improvements in 10 envelopes or covers for wire coils.

The present invention is designed as an improvement on those certain devices secured to us by Letters Patent Nos. 744,467 and 746,447, dated November 17 and December 8, 1903, respectively, for improvements in wire-covers; and the object is to simplify and improve the means employed for securing the meeting edges of the envelop when the device is in position on the coil of wire. In these prior cited 20 patents a lacing is employed in the first named to draw and hold together the edges of the envelop about the wire coil, and in the other radially-arranged straight straps are used for the purpose, while in the present device the 25 free edges of the envelop are held together by means of triangular strips or pieces having their bases secured to one of the sides of the envelop and straps extending from the points of the pieces to engage buckles secured 30 to the other side of the envelop.

We have fully and clearly illustrated our improvements in the annexed drawings to be taken as a part of this specification, and reference being thereto had, Figure 1 is a view of 35 the envelop or wire-cover extended, showing the triangular fastening pieces and straps and the buckles with which they connect. Fig. 2 is a side elevation of the envelop or cover as it appears when it is secured about a coil of 40 wire. Fig. 3 is a vertical section taken on the line 3-3 of Fig. 2.

In the drawings the same parts appearing in the different illustrations are designated by like reference notations, and referring thereto, 45 A designates the envelop, cover, or wrapper made of some strong textile or other suitable flexible material and made of such determined capacity as to suit the purpose of completely surrounding a coil of wire to which it may be 50 applied. In Fig. 1 the envelop is shown as

extended and as composed of coincident side pieces made up of curved sections 1 2 3, strongly sewed together at their meeting ends and at the back, substantially as indicated in the drawings, so that when the ends 55 are positioned in contact a circular tubular casing or envelop will be formed, as seen in Fig. 2 of the drawings. To the free inner edge of one of the sides of the envelop are secured scalene triangular fastening-strips 4, 60 adapted to lie diagonally on the opposite side of the casing, as shown, and thus bind the inner meeting edges together. To the ends or points of the triangular fastening-strips are secured leather straps 5, which engage with 65 buckles 6, secured to the side opposite to the one to which the strips 4 are fastened.

By making the fastening-strips of scalene triangular shape (shown) a broad base is obtained for connection to the edge of the envelop, which cannot be had when buckles and straps are used, and by arranging the buckles in line with the center of the triangles the pull is substantially equal at all points of the base, as indicated in the drawings, thus protecting 70 a comparatively extended distance of the edges. The ends of the envelop are held tight about the coil by means of straps 7, fastened adjacent to the meeting ends of the envelop, as seen in Fig. 2 of the drawings. 80

It will be observed from Fig. 2 that the straps on the ends of the triangular strips extend at a tangent with respect to an imaginary circle within and concentric to that formed by the inner periphery of the envelop and that 85 the buckles are in line with the straps. For this reason when the straps are tightened they have a tendency to contract the envelop in a circumferential direction, so as to cause it to fit more closely upon the wire coil. Furthermore, 90 it will be observed that the triangular strips 4 are preferably attached to one of the sections, such as 1, and the buckles are preferably attached to the adjacent section, such as 2, this construction being rendered possible by reason of the tangential relation which the triangular strips and straps possess, as 95 above noted. For this reason when the straps are tightened they serve not only to contract the envelop, as above set forth, but they also 100

serve to aid the stitching in holding the sections of the envelop together.

Having thus described our invention, what we claim is—

- 5 1. A wire-coil envelop consisting of sections having scalene triangular strips secured at their bases to the edges of the sections and provided with straps extending tangentially to an imaginary circle within and concentric to that formed by the inner periphery of the envelop, said envelop also having sections provided with buckles in line with the straps, whereby the strap on one section may be engaged with the buckle on the next adjacent section.
- 10 2. The combination with a wire-coil envelop, of fastening means consisting of scalene tri-

angular strips having their bases secured to the edge of one side of the envelop and straps extending from the points of the triangles tangentially to an imaginary circle drawn within and concentric to that formed by the inner periphery of the envelop, and buckles secured to the other side of the envelop in line with the straps, whereby the tightening of the straps causes a reduction in the diameter of the envelop.

In testimony whereof we affix our signatures in presence of two witnesses.

HUGH C. BOYLE.
JOHN MAUM.
